ROBERT HUNTER, OF NEW YORK, N. Y.

Letters Patent No. 97,924, dated December 14, 1869.

IMPROVEMENT IN PROPELLING-APPARATUS.

The Schedule referred to in these Letters Patent and making part of the same.

To all whom it may concern:

Be it known that I, ROBERT HUNTER, of No. 9 Brevoort Place, in the city of New York, doctor of medicine, have invented an Improvement in the Propeller for Steam-Vessels, for which Letters Patent of the United States of America were granted to me on the 11th day of August, 1868.

This improvement consists in attaching the propelling-structure to the outer end of a horizontal shaft, working through a stuffing-box or other guides, and connecting the other end of such shaft to the lower end of a naked vertical lever, swung on an axis above its centre.

The propelling-structure, adjusted as afore described, is operated by an engine, attached to the upper end of the vertical lever, precisely as described in the specification of the invention for which Letters Patent of the United States, numbered 80,960, have already been granted me.

The form of the propelling-structure may be made of any desired shape, round, square, oblong, oval, &c., and the floats placed either vertically or horizontally.

The engine may be directly attached to the upper end of the lever by the connecting-rod of the piston, or the oscillation of the lever may be obtained from a crank-movement. In the former case a horizontal engine must be employed, but in the latter, either a vertical or horizontal engine will answer.

Whenever it is desirable to multiply the oscillation of the lever beyond the strokes of the piston of the engine, this may readily be effected by employing the crank and ordinary cog-wheel gearing, but with some loss of power.

It will be seen that the distinction between this invention and the one for which Letters Patent were granted me on the 11th day of August, 1868, consists wholly in the employment of the horizontal shaft. In all other respects, the combination is precisely the same.

The advantage gained by connecting the vertical lever to the propelling-structure, by a horizontal shaft working through a stuffing-box in the stern of the vessel, is threefold:

First, it is applicable to a class of canal-boats, constructed with square sterns, which does not admit of the oscillation of the lever under the stern;

Secondly, the lever is protected from external injury by reason of being operated wholly within the vessel, while no change is made in the leverage employed for propulsion; and

Thirdly, we get a more direct propelling-stroke.

This invention differs from all other propellers which are attached to a horizontal shaft, working through a stuffing-box in the stern, in its greater simplicity of construction, and in reciprocating the propelling-structure by connecting the inner end of the shaft to the lower and longest end of a vertical lever.

The advantage of the vertical over the horizontal lever is far greater than at first sight would appear. By employing horizontal levers within the hull of a vessel, they are of necessity very short, whereas vertical levers may be employed which extend from the upper deck to the bottom of the hold. The length of the propelling-stroke depends on the length of the lever employed.

The distinction, therefore, between short horizontal levers, such as have hitherto been employed, and the long vertical lever used by me, in actual results is very marked. I get a long propelling-stroke for a very short stroke of the piston; and by increasing the length of the lever below the axis on which it swings, I give the water a greater mechanical advantage, and reduce the slip of the paddle to its minimum quantity.

If the object were to push the water before the propelling-structure, a short lever would be the best adapted, but since the object is to make the water, against which the propeller impinges, as nearly as possible a fixed abutment, the lever should always be made as long as the vessel will allow, and the propeller diminished in size to that point which will barely prevent slip. If the lever is short, the propeller must be large and cumbersome. If the lever is long, a much smaller propeller will obtain the same resistance from the water. In every case, to obtain a satisfactory propulsion, the length of the lever and the size of the propeller must be so apportioned that it shall require more power to displace the water before the propelling-structure than to move the vessel. The propeller should hold against the water, as to a fixed point, and the vessel move on.

This combination may also be employed outside the hull of a vessel, in the manner shown in fig. 3, but in that case the horizontal shaft will not pass through a stuffing-box, but be supported by strong iron guides, bolted to the side of the vessel.

In the accompanying drawings—

Figure 1 is a vertical longitudinal section of the stern portion of a vessel, with my invention applied.

Figure 2 is an elevation of the stern.

Figure 3 is a perspective view of my propelling-apparatus, as externally arranged.

Figure 4 is a perspective view, representing the propeller attached directly to the vertical lever, and the latter mounted reversibly in the transverse rock-shaft.

Figures 5, 6, and 7, represent various forms of propellers which may be used as substitutes for those shown in the other figures.

A represents the long arm of a lever worked by

engine D, through the pitman E, connected to the short arm A'.

B shows the connecting-gear, which attaches the lower extremity of the lever A to the horizontal shaft C, to which the propeller G is adjusted, either by means of the curved iron H or any other suitable contrivance.

S represents stuffing-boxes, through which the horizontal shaft works, and

T, guides, employed with external arrangement of said shaft.

From the foregoing, it will be apparent that the reciprocating movement of the piston-rod P, moving in the engine D, will cause the lower end of the lever A to vibrate or oscillate between the points l k, and by means of the connecting-rod B, a direct action is given to the shaft C and propeller G.

The pivoted propeller-floats may be supported by suitable stop-bolts, which being withdrawn by a rod and wheel, permit the floats to fall through the frame and open in the opposite direction. This or other suitable device is employed to reverse the propellers, for changing the motion of the vessel.

When it is deemed unadvisable to employ the horizontal shaft outside the hull of a vessel, in the man-

ner described, the propeller may be directly attached to a vertical lever adapted to turn upon its axis for reversing, or two or more such levers, so adjusted, may be oscillated at the side or under the run of a vessel, for the purpose of propelling the vessel.

By attaching the propellers to the long arm of the lever, so as to give the mechanical advantage to the water, which constitutes the resisting-medium, I cause less disturbance or displacement of water, and am thus enabled to use my device with good effect, especially in the propulsion of canal-boats, where a high speed is not required, and where it is of especial importance to avoid undue agitation of the water.

I claim, as new—

The combination and arrangement of the long lever-arm A, short arm A', propeller-rod C, pivot-float propeller G, and guides S or T, operating substantially as and for the purposes herein set forth.

To the above specification of my improvement in propellers, I have signed my hand, this 21st day of September, A. D. 1868.

ROBERT HUNTER.
